UNITED STATES PATENT OFFICE.

WILLIS S. FARNSWORTH, OF PETALUMA, CALIFORNIA, ASSIGNOR TO COIN CONTROLLED
LOCK COMPANY, OF PETALUMA, CALIFORNIA.

COIN-CONTROLLED LOCK AND CONVEYER.

1,034,604.

Specification of Letters Patent.

Patented Aug. 6, 1912.

Application filed February 23, 1911. Serial No. 610,182.

To all whom it may concern:

Be it known that I, WILLIS S. FARNSWORTH, citizen of the United States, residing at Petaluma, in the county of Sonoma and State of California, have invented new and useful Improvements in Coin-Controlled Locks and Conveyers, of which the following is a specification.

This invention relates to coin controlled locks, and particularly pertains to a device for controlling the operation of a lock by means of coins, slugs or other tokens.

It is the object of this invention to provide a coin operated mechanism for controlling locks, by means of which the lock can be operated only by the depositing of a proper coin or token.

A further object is to provide a coin-controlled device which is adapted to be applied to the ordinary cylinder locks now in use, without altering the lock structure to any extent, and which is simple in construction, economical in manufacture, durable, not liable to get out of order and efficient in operation.

Another object is to provide means by which a series of superposed locks may be operated separately by separate coins and the coins conveyed through a single chute 30 to a common receptacle as is desirable in locker construction.

The invention consists of the parts and the construction and combination of parts, as hereinafter more fully described and claimed, having reference to the accompanying drawings in which—

Figure 1 is an elevational view of a portion of a locker cabinet showing the invention as applied. Fig. 2 is a view in elevation of the rear of the lock with the lock removed, illustrating the positions assumed by the parts in the first stage of their operation following the deposit of the coin. Fig. 3 is a similar view showing the second position of the parts. Fig. 4 is a detail view of a cylinder lock, depicting the manner in which the cylinder is blocked and prevented from being operated. Fig. 5 is a vertical section on the line X—X, Fig. 3. Fig. 6 is a horizontal section on the line Y—Y, Fig. 5. Fig. 7 is a detail view of a cylinder lock with parts broken away showing the manner in which the key is blocked and prevented from being removed.

This invention is especially designed for

use on the doors of lockers, cabinets, closets and the like, where it is advantageous to collect toll for admission to or for the rental of the space behind the door. It is particularly applicable to use on lockers in hat and cloak rooms, and other places where a number of safe deposit boxes and the like are installed and where each separate door is provided with a special lock and key.

This device is so designed that the key 65 cannot be removed from its respective lock until a certain coin has been deposited, nor a lock locked or unlocked without the previous dropping of a coin, but when the required coin is deposited, the customer or 70 user may lock the desired door and remove the key for opening the door at a future time. It is also so constructed that the locker can be used but once for a single coin.

In the drawings A represents a door which may be hingedly mounted in any desired manner in a frame B.

C is the barrel of a cylinder lock of any suitable type mounted in a cylinder casing 80 D and having the usual loose pins 2, which are actuated by the insertion of a key 3 in the keyhole 4 extending longitudinally through the barrel C. A bit or projecting pin 5 is suitably attached to the inner end 85 of the barrel C and is adapted to actuate similar bits 5' on a sleeve on the barrel, one of which bits 5' works in a recess in one side of a latch bolt 6, to advance and retract the latch bolt within the lock casing 7 when 90 the barrel C is rotated properly, as shown in Figs. 2 and 3. That latch bolt 6 is normally retained in its innermost position by means of a spring 8, which bears against and opposes the movement of one of the 95 bits 5' and thus offers a resistance to any outward movement of the latch bolt 6.

My attachment comprises a rockable lever arm 9 which is mounted on a pivot pin 10 projecting upwardly from the rearwardly 100 extended portion of the latch bolt 6. This lever 9 projects through a slot in the casing 7 and is loose on the pin 10. The inner end of the lever 9 is counterweighted so as to overbalance the outer end and normally 105 retains the latter in its uppermost position, in which position a notch 11 on the upper edge of the lever will be engaged by the upper end of the slot in the casing 7 when the bolt 6 is in its retracted position. When 110

the parts are in this position, it is manifest that the latch bolt 6 cannot be advanced by the operation of the key 3 and its cylinder, the engagement between the lever 9 and the casing 7 preventing its forward movement.

In the application of this invention, the lock as just described, is preferably placed in the door jamb or casing B, instead of on the door A as commonly practised, the purpose of which is to admit of the ready disposition of a coin-operating mechanism as will now be described. The lock case 7, carrying the cylindrical casing D, barrel C and the latch bolt 6, is mounted on a plate 12 which is designed to be countersunk in the back of the vertical jamb member B, and flush therewith. Formed on the inner face of the plate 12 to one side of the lock case 7 is a pair of vertically extending spaced ribs or flanges 13-13', which project outward against a transparent plate 12' mounted in the jamb B to form a guide slot for a coin. A portion of the rib 13, nearest the lock-case 7, is removed so that the outer end of the lever 9 will project therebeyond into the path of a coin which may pass downward between the ribs 13-13', as shown in Fig. 2. Pivotally mounted on the plate 12 below the outer end of the lever 9 is a normally vertically disposed curved lever 14 on the upper end of which is formed a knob 15 which is adapted to be engaged by a notch 16 on the underside of the outer end of the lever, as will presently be described.

The operation of the invention is as follows: Assume that the parts to be in the normal position shown in Fig. 2 with the key 3 in the cylinder C, the door A open, and the latch 6 retracted. In this position it will be seen that the door A cannot be locked in the closed position by reason of the notch 11 in the lever 9 being engaged by the casing 7, which prevents the necessary turning of the cylinder B to throw the latch bolt 6. Neither can the key 3 be withdrawn from the cylinder C, by reason of the latter being slightly turned to one side when the lever 9 is in engagement. In this position the loose pins 2 are not in alignment with the pins (not shown) in the cylinder D, but bear against the walls inside the cylinder, as shown in Fig. 7, thus blocking the key 3 against removal. It is understood that with locks of the Yale type a key can only be withdrawn when the keyhole and key stand in a certain position, usually vertical. It being desired to lock the door A and remove the key 3, a coin of the proper value, for instance, a five cent piece, is inserted in a slot 17 formed in the casing B, and which communicates with the guide slot on the plate 12, through an inclined chute 18. This coin, traveling down inclined chute 18 drops

upon the trap-lever 9 to depress the outer end of the latter as shown in Fig. 2, thus releasing the notch 11 from the casing 7, and causing the notch 16 to engage the knob 15 on the lever 14. The knob 15 acts as a stop and arrests the downward movement of the coin and causes its entire weight to rest on the outer end of the lever 9 to maintain it in its lowermost position. In this position the lock end of the lever 9 is dropped sufficiently to disengage the notch 11 from the casing 7, thus permitting the barrel C to be rotated by the key 3 in the direction of the arrow, Fig. 4, so as to throw the latch 6 out of the casing 7 into engagement with a keeper on the door A previously closed, and thus prevent its being opened. On turning the barrel C as just described, the swinging lever 9 is drawn forward by the pin 10 on the bolt 6, so that the coin 19 will drop between the end of the lever 9 and the flange 13' upon the semi-crescent shaped lower end of the lever 14 which has been previously disposed across the chute by the forward movement of the lever 9, where it comes to rest, and is sustained as shown in Fig. 3. The door A being now closed and locked, and the barrel C revolved so as to throw the keyhole 4 into a vertical position, permits of the removal of the key 3, as is well known in cylinder lock construction. When it is desired to unlock the door A the key 3 is inserted in the barrel C in the usual manner, and the barrel returned to its normal position. As the barrel C is rotated the bolt 6 is retracted so as to permit the door A to swing outward; the lever 9 being engaged with the bolt 6 returning to normal. As the lever 9 moves backward the lever 13 is rocked on its pivot so as to release the coin 19 and permit it to drop downward into a chute 20 which is formed by mounting a vertically disposed channel mold 26 on the back of the casing D as shown in Fig. 5. The moment the coin is released, the lever 9 is rocked on its pivot to release the knob 15 from the notch 16 and cause the notch 11 to return into engagement with the casing 7 which again blocks the lock until another coin is deposited in the slot 17.

Means are provided for adapting the device for use with coins of various sizes and denominations. This is accomplished by adjustably mounting a bar 21 on the plate 12, adjacent the flange 13'. This bar 21 is disposed parallel with the flange 13' and is designed to be placed at several points remote therefrom in order to regulate the width of the coin passage. For instance, when the bar 21 is placed in contact with the flange 13', a five cent piece will in passing through the coin passage, drop upon and actuate the lever 9, while a one cent piece or a dime would pass on down the slot 130.

without affecting the lever. By setting the bar 21 away from the flange 13' the coin passage will be narrowed to fit either a dime or a penny so that the lever 9 will be operated thereby. As a means of gaging the position of the bar 21 a series of notches 22 are formed on its upper end which are adapted to engage the flange 13', each notch representing the distance the bar should be spaced from the flange 13 for the several sized coins. This bar 22 is held in place in its various positions by means of a clamp screw 24 which is threaded into the bar and extends through a slot 25 in the plate 12.

15 An important feature of this invention lies in the arrangement of the plate 12 and the lock mechanism thereon, in the jamb B. This becomes apparent when a series of superposed doors A are employed; as in a locker cabinet, where if the lock is placed on the door it is obviously necessary to employ separate coin receptacles in each door, or provide more or less complicated means for delivering the coin from the door to a chute.

20 In the arrangement here disclosed these difficulties are obviated by the use of the vertically disposed channel mold 26 which may be made of either wood or metal on the back of the jamb B, into which the coins are dropped from the lever 14; the coins entering the channel mold 26 under the lower edge of the plate 12. This mold 26 may be of any desired length and may lead to any suitable receptacle at its lower end. It will be observed that the coin 19 will be sustained on the curved lever 14 during the time the door A is closed and locked, so that by perforating the casing B at 27, opposite the position occupied by the coin, the use of 40 any but the required token can be detected.

From the foregoing it will be seen that I have provided a means by which a door may be locked only by the depositing of a certain coin, which is particularly adapted for use 45 on lockers, safe deposit boxes and the like. In this instance, the door A is swung to normally stand in an open position, and the bolt in the lock in the casing B being retracted and prevented from being advanced 50 until the lever 9 is released by the proper coin, the locker space cannot be utilized and locked against access by the unauthorized persons until such coin is deposited. This being done, articles may be placed within 55 the locker and the door closed and locked and the key removed. The use of spurious coins, slugs, or other tokens than those desired, is avoided, by reason of their being retained on the lever 14 in line with the perforation 27 during the time the door A is

closed and locked in plain view of the attendant; this coin dropping to a suitable till through the channel 26 when the door A is again unlocked.

Having thus described my invention, what I claim and desire to secure by Letters Patent is—

1. In a lock having a coin chute and a lever extending in the chute to be rocked by the weight of a coin, of means for adjusting the coin chute to receive different sized coins, consisting of a vertically disposed bar, a clamp screw for retaining the bar in place, stepped up notches formed on the upper end of the bar, and a rigid member engageable by any one of the notches to gage the position of said bar in relation to said lever.

2. In a coin-controlled lock, the combination with a coin chute, of a normally retracted latch bolt, key means for reciprocating the bolt, a dog mounted on and movable with the bolt and normally holding the bolt against movement and having a portion which projects normally into the path of the coin, and a detent normally out of the path of the coin controlled by the dog.

3. In a coin-controlled lock, the combination with a coin chute, of a normally retracted latch bolt, key means for reciprocating the bolt, a dog mounted on and movable with the bolt and normally holding the bolt against movement and having a portion which projects normally into the path of the coin, and a detent separate from, but engaged by the dog and held thereby normally out of the path of the coin controlled by said dog.

4. In a coin-controlled lock, the combination with a coin chute, of a normally retracted latch bolt, key means for reciprocating the bolt, a detent normally out of the path of the coin, a dog mounted on and movable with the bolt and normally holding said bolt against movement and having a portion which projects normally into the path of the coin, said detent being loosely connected to said dog and controlled thereby and adapted to be thrown into the path of the coin when the bolt is thrown forward to support the coin, said detent being again thrown out of the path of the coin when said bolt is retracted.

In testimony whereof I have hereunto set my hand in the presence of two subscribing witnesses.

WILLIS S. FARNSWORTH.
